(57) **ABSTRACT**

A brand ambassador providing end-users with a stealth device incorporating silicone chamber technology facilitating the storage of pre-rolled cigarettes, a one-hit pipe, an area for securely stashing cannabis flower, and a built-in chamber for a disposable lighter.

1 Claim, 1 Drawing Sheet

FATTY CADDY BOWL IN ONE

BACKGROUND OF THE INVENTION

The present invention relates to smoking accessories providing an end-user with a turnkey solution; specifically, one designed with silicone chambers suitable for pre-rolled cigarettes and a one-hit pipe, an area for ground cannabis or flower, and a built-in area suitable for storage of a disposable lighter, encapsulated in a brand ambassador with a closeable head.

SUMMARY OF THE INVENTION

Cannabis end-users need a few things; a lighter, a cannabis cigarette, maybe a one-hit bat, a place to secure medicine. The majority of cannabis dispensaries world-wide sell each of these products individually, and often in pairs. It's not uncommon for an individual to exit a dispensary with a bag containing every item listed above. The Fatty Caddy Bowl in One is the first device of its kind; in that it accommodates each of the above elements—in a self-contained stealth device.

BRIEF SUMMARY OF FIG. 1

FIG. 1 is a frontal view of The Fatty Caddy Bowl in One. The elements of the invention are clearly labeled 1a. 1b. 1c. 1.d.

DETAILED SUMMARY OF FIG. 1

FIG. 1 illustrates The Fatty Caddy Bowl in One, a brand ambassador supporting the normalization of medical and recreational cannabis.

The plastic device is a smoking accessory, offering end-user cannabis enthusiasts with a turnkey and stealth solution.

The components of Diagram 1:

A plastic brand ambassador with a hinged head that opens to reveal the following elements:

- 1a. an insert suitable for storage of disposable lighter.
- 1b. silicone tube for storage of pre-rolled cigarette.
- 1c. silicone tube for storage of one-hit pipe.
- 1d. silicone chamber with slide for storage of cannabis.

What is claimed:

1. A smoking accessory with a hinged lid, comprising of three vertically oriented storage areas, wherein in one storage area is for holding a lighter, another storage area for holding a pre-rolled cigarette, the third storage area for holding a one-hit pipe, and a horizontally sliding silicone chamber which can slide open and accommodate an area for dried plant matter.
